CIGARETTE DISPENSER

William Freudlich, Jackson Heights, and Leslie Szikla,
New York, N. Y.

Application June 29, 1953, Serial No. 364,546

1 Claim. (Cl. 221—250)

This invention relates to cigarette dispensers.

It is an object of the present invention to provide a cigarette dispenser which includes means for feeding a cigarette through the top of a container, said feeding means being operable from the outside of the container.

It is another object of the present invention to provide a cigarette dispenser of the above type which includes baffle means for feeding the cigarettes to the feeding means in a substantially vertical, loose and operable manner.

It is still another object of the present invention to provide a cigarette dispenser of the above type which includes a cover having a hinged portion or portions permitting the outward movement of the cigarette when fed.

Other objects of the present invention are to provide a cigarette dispenser bearing the above objects in mind which is of simple construction, inexpensive to manufacture, has a minimum number of parts, is easy to use and efficient in operation.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a perspective view of a cigarette dispenser embodying the features of the present invention and shown in operative use.

Fig. 2 is a sectional view taken along the line 2—2 of Fig. 1 and showing the cigarette being removed after feeding.

Fig. 3 is a transverse sectional view taken along the line 3—3 of Fig. 2.

Fig. 4 is an enlarged fragmentary plan view of the cover of the dispenser showing the hinged door permitting the upward movement of the cigarette.

Fig. 5 is a fragmentary perspective view of the dispenser casing, shown partly broken away to illustrate the construction of the bottom wall.

Fig. 6 is a fragmentary perspective view of a modified form of the present invention.

Fig. 7 is a perspective view of a still further modified form of the present invention shown partly broken away to show the interior construction.

Fig. 8 is a perspective view of a still further modified form of the present invention.

Referring now to Figs. 1 through 5, 10 represents a rectangular casing of metal, plastic or other suitable material open at the top and provided in one end wall 11 with an elongated opening 12.

The front wall 13 of casing 10 is provided with a circular opening 14 therethrough.

A pin 15 is rotatably mounted within the opening 14, being peened at both ends, and serves to rotatably mount a feeder arm 16 consisting of a circular head portion 17 and an elongated arm portion 18, the feed member 16

2

being rotatably mounted on the inner face of the front wall 13. The head portion 17 extends outwardly through the slot 12 in a serrated portion 19 adapted to be moved by the thumb, as shown in Fig. 1. The head portion 17 is also provided within the casing 10 with a cutout 20 which serves to receive the free end of a spring 21 suitably secured at its other end to the end wall 11 on the inner face thereof (Fig. 2). The arm 18 terminates in a finger 22 extending across a portion of the open bottom 10 of the casing 10 at substantially right angles to the arm 18.

A bottom wall 23 is integrally formed or suitably secured to the bottom of casing 10. This bottom wall 23 at one end on the inner face thereof and at one side is provided with a rectangular recess 25 which receives the finger 22, permitting the upper surface of the latter to be disposed in the same plane as or below the inner surface of bottom wall 23. It will be noted that the recess 25 is smaller than the diameter of cigarettes 34, preventing the latter from entering the recess. The spring 21 will serve to retain the finger 22 in abutment with the recess 25, as shown in Fig. 2, until the finger 22 is moved upwardly by pressing downwardly on the serrated portion 19 with the thumb, as shown in Fig. 1.

25 A baffle 27 (Figs. 2 and 3) is suitably secured along one longitudinal edge to the inner face of back wall 28, the other longitudinal edge of the baffle 27 terminating short of the front wall 13. A second baffle 29 is suitably secured along one longitudinal edge to the inner face of 30 the front wall 13, the other longitudinal edge of the baffle 29 terminating short of the back wall 28. The longitudinal edge of the baffle 29 adjacent the front wall 13 is provided with an elongated cutout 30 permitting the movement of the arm 18. It will be noted that the 35 upper end 30a of cutout 30 serves to abut and thereby limit the upward movement of arm 18. The baffles 27 and 29 are an essential part of the present invention, as they prevent the cigarettes 34 from assuming a diagonal position as they are shaken forwardly toward the finger 22. Such diagonal disposition, if not prevented, would result in bending of the cigarettes when the finger 22 is actuated and would make it impossible to eject the cigarettes at all.

40 45 A top wall 31 of plastic or other suitable material is provided on its inner face with a peripheral groove 32 permitting the same to be snapped or slid into the upper end of the casing 10, the cover 31 being then retained in this manner by crimping the upper edges of the casing 10, as at 33. One end of the cover 31 is provided with a 50 rectangular cutout 35 (Fig. 4) which receives the tongue 36 of a top flap 37. A pin 38 (which can be provided with a spring) passes through the end of cover 31 surrounding the cutout 35 and through the tongue 36, thus 55 rotatably mounting the flap 37.

It will be appreciated that more than one such flap 37 may be provided, if desired, such plurality of flaps being transversely aligned.

In use, the casing 10 is filled with cigarettes through 60 the open top of the casing and the top closure 31 then snapped into position, the finger 22 being retained in the recess 25 by the action of spring 21. The casing is then gripped in a natural manner as shown in Fig. 1, and the serrated portion 19 rotated downwardly with the thumb, 65 thus moving the finger 22 upwardly to the dotted line position of Fig. 2, this movement forcing the cigarette 39 supported thereon upwardly through the flap 37 where it is grasped between the fingers of the other hand. It will be noted that the serrated portion 19 is rendered substantially invisible, thus causing the cigarettes to rise in an astonishing and novel manner. When the serrated portion 19 is released by the thumb, the spring 21 will

urge the finger 22 back into the recess 25 where it will remain until the next dispensing operation. The baffles 27 and 29 permit cigarettes to be shaken towards the end wall 34 through the spaces between the longitudinal edges of the baffles and the adjacent walls of the casing in a substantially vertical position, and insuring a loose distribution of the cigarettes when they reach the finger 22.

The outer peripheral edges of the top 31 and bottom 23 are bevelled to avoid sharp edges and to improve the appearance.

Referring now to Fig. 6, there is shown a modified form of the invention differing from the first form in the feeder mechanism.

In this form, the casing 10' is provided with an end wall 11' now devoid of the opening 12, the front wall 13' being provided with an arcuate slot 14' in which rides a shaft 60. A knob 41 is suitably secured to the outer end of shaft 60 while a feeder arm 42 pivotally mounted at its upper end by a shaft 61 is suitably secured to the inner end of the shaft 60. The lower end of the feeder 42 is integrally formed with a laterally bent finger 22' for the same purpose as the finger 22 of the first form. It will be noted that the spring action is the same as hereinbefore described.

In other respects the form of the invention shown in Fig. 6 is the same as that shown in Figs. 1 through 5, and like reference numerals identify like parts throughout the several views.

Referring now to Fig. 7, there is shown a still further modified form of the invention wherein the casing 10'' is provided with an end wall 11'' having a relatively large elongated rectangular opening 44. A manually operable slide 45 is provided on its under surface with serrations 46 in mesh with the serrated portion 19 of the feeder member 16, the slide 45 being integrally formed at each end with flat extensions 47 which slidably abut the undersurface of the end wall 11''. Thus, the slide 45 is maintained in sliding contact with the inner surface of end wall 11'' by the feeder member 16, as will be obvious. Upon sliding the slide 45 away from top closure 31, the trigger 22 will be rotated toward top closure 31 to dispense cigarettes in a manner similar to the first form.

Link means, not shown, may, of course, be provided connecting flap 37 and feeder member 16, as will be apparent to those skilled in the art.

In other respects the form of the invention shown in Fig. 7 is the same as that shown in Figs. 1 through 5, and like reference numerals identify like parts throughout the several views.

Referring now to Fig. 8, there is shown a still further modified form of the invention, differing from the previous forms in the provision of an L-shaped transparent window 48 in side wall 13^a, the latter being formed of metal or other non-transparent material, permitting the cigarettes 34 to be displayed. One end of cover 31^a terminates short of end wall 34 of casing 10^a and is provided with rectangular cutouts 35^a which receive the tongues 36^a of three top flaps 37. A pin 38^a (which can be provided with a spring) passes through the end of cover 31^a surrounding the cutouts 35^a and through the tongues 36^a, thus rotatably mounting the flaps 37.

In other respects the form of the invention shown in Fig. 8 is the same as that shown in Figs. 1 through 5, and like reference numerals identify like parts throughout the several views.

5 The side walls of the casing may, of course, be slidably mounted, as will be apparent to those skilled in the art.

While we have illustrated and described the preferred embodiments of our invention, it is to be understood that we do not limit ourselves to the precise constructions herein disclosed and the right is reserved to all changes and modifications coming within the scope of the invention as defined in the appended claim.

Having thus described our invention, what we claim as new, and desire to secure by United States Letters Patent is:

15 A cigarette dispenser comprising a hollow casing having bottom, front, back and end walls and being open at the top, said casing being adapted to contain a pack of loose cigarettes, top closure means for said casing, said top closure means including a flap at one end of said top closure means, said flap being pivotally mounted for outward movement, a cigarette feeding member rotatably mounted on the front wall of said casing, said feeding member comprising a unitary transverse finger member 20 adapted to be received in a recess in the bottom wall and to underlie the bottom end of a cigarette dispensed below said flap and a head portion, said head portion having serrations on its periphery projecting beyond one of the end walls of the casing, and a cutout portion in one face 25 thereof, an elongated spring having one end secured along the front wall of the casing and having its other end extending into said cutout for retaining the feeding member in a retracted position, with means for guiding the 30 cigarettes to the feed finger comprising baffles mounted in staggered relation on the front and back walls of the casing, said baffles projecting substantially to the middle of the casing, one of said baffles and its front wall connection being removed to form a slot in which the feeding member moves to discharge a cigarette from the casing.
